E. PULSIFER.
THROTTLE VALVE CONTROLLING MEANS.
FILED DEC. 5, 1921.

FILED DEC. 5, 1921.

Inventor: Ernest Pulsifer
Full Name: Ernest Pulsifer
Address: 107 Kinnear

UNITED STATES PATENT OFFICE.

ERNEST PULSIFER, OF SALEM, MASSACHUSETTS, ASSIGNOR OF TWO-THIRDS TO FRANK PULSIFER AND WARREN PULSIFER, BOTH OF SALEM, MASSACHUSETTS.

THROTTLE-VALVE-CONTROLLING MEANS.

Application filed December 5, 1921. Serial No. 520,050.

To all whom it may concern:

Be it known that I, ERNEST PULSIFER, a citizen of the United States, and a resident of Salem, county of Essex, State of Massachusetts, have invented an Improvement in Throttle-Valve-Controlling Means, of which the following is a specification.

In the operation of steam propelled automobiles, which do not employ a clutch between the engine and the driving wheels, but rely entirely on the throttle valve to control the engine, it has been customary to control the throttle valve by means of a hand lever located at the middle of the steering wheel, and, so far as I am aware, it has not been considered practicable to provide foot-operated throttle controlling means in conjunction with the hand operated means ordinarily employed. Moreover, a foot operated throttle is considered dangerous, where the engine is always connected to the drive, as the engine is liable to be started by accidental depression of the foot operated means.

The objects of my invention are to provide a simple and effective means whereby the throttle of a steam automobile may be controlled either by hand, through a swinging handle at the steering wheel, or by a depressible pedal, or other foot controlled means, so arranged that each may be operated independently of the other, and the hand-operated means may be operated to close the throttle and at the same time may be moved to render the foot-controlled means inoperative.

I accomplish these objects by providing a hand operated means and an independent foot operated means each arranged to operate a single throttle controlling means independently of the other, and by providing means whereby, when the hand-operating means is moved to, or rearwardly of the position in which it causes the throttle to be closed, it will also disconnect the foot operated means from said controlling means, or otherwise render the same inoperative. For a more complete understanding of my invention reference is made to the accompanying drawing in which:

Fig. 1 is a side sectional view of the front portion of an automobile showing, in a general way, the application of an embodiment of my invention thereto.

Fig. 2 is a perspective view of the specific form of controlling means which I preferably employ.

Fig. 3 is a longitudinal section taken at line 3—3 of Fig. 2.

Figs. 4, 5 and 6 are cross sections at line 4—4 of Fig. 3.

Fig. 7 is a cross section, at line 7—7 of Fig. 3.

In Fig. 1 of the drawing, the application of an embodiment of my invention to a steam automobile is illustrated in a general way, and, as shown thereon, the floor 10 of the body has the usual steering post 12 mounted therein, within which a rod 13 is rotatably mounted, said rod having a hand operated arm 14 at its upper end, and a bevel gear 15 at its lower end arranged to mesh with a similar gear 16. The gear 16 has a crank arm 17 thereon which is connected by a link 18 to the operating arm 19. A push rod 20, having a head 21, adapted to be pressed by the foot, is conveniently arranged in the floor 10 and is directly connected at its lower end to the operating arm 22.

A base plate 23, having arms 24, 25 thereon, is secured to the underside of the floor, so that said arms project downwardly, and a shaft 26 is mounted to oscillate in bearings 24^a and 25^a, respectively, formed in the ends of said arms. A crank arm 27 is secured on one end of the shaft 26, in engagement with the adjacent end of the bearing 24^a, and a flange 28 is formed on the opposite end of the shaft, which engages the end of bearing 25^a, so that the shaft is held against longitudinal movement therein. The arm 27 is connected by a link 29 to one arm of a bell-crank lever 30, which is pivoted on the floor 10, the other arm thereof being connected to the throttle valve 31, which admits steam from the boiler to the engine. A spring 32 is connected to the arm 27 and is under tension to move the throttle valve to closed position, when opened, and to retain it in closed position.

As thus far described the mechanical devices connected to the arms 19, 22 and 27 are merely illustrative of connections which may be employed, but it is considered that various other forms of connections may be advantageously employed.

According to my invention a segmental

2
sleeve 19^a is formed with the arm 19 and a segmental sleeve 22^a with the arm 22, said sleeves being arranged end to end on the shaft 26 and occupying all the space between the adjacent ends of the bearings 24^a, 25^a, so that they are held against movement lengthwise of the shaft, but are free to be oscillated thereon. As shown in Fig. 2, a segmental portion of the sleeve 19^a, which is substantially less than a semi-circumference, is cut away, thereby providing oppositely disposed shoulders 19^b, 19^c and, in like manner, a similar segmental portion is removed from the sleeve 22^a, providing a shoulder 22^b.

A pin 33, or other suitable form of fixed abutment, is mounted in the shaft 26 approximately midway of the sleeve 19^a and in position to be engaged by the shoulder 19^b, so that, when the hand lever 14 is moved to open the throttle, the sleeve is swung on the shaft until its shoulder 19^b engages the pin 33, as shown in Fig. 4, and then, on further movement the shaft will be moved so as to swing the arm 27 in a direction to open the throttle valve, as shown in Fig. 5.

A beveled tooth 34 is arranged in a slot 26^a, which extends longitudinally of the shaft 26, and for a short distance beneath each bearing 24^a, 25^a, and a bowed spring 35 is arranged in the bottom of said slot and acts to push said tooth outward.

The tooth 34 has reduced end portions which, extend beneath the bearings 24^a, 25^a and, by engaging therewith, act as stops to limit its outward movement by the spring 35.

With the parts in the position of Fig. 2, if the push rod, or pedal 20 is depressed, the sleeve 22^a will be swung so that its shoulder 22^b will engage the front side of the tooth as shown in Fig. 7, and thereby cause the shaft 26, on further movement of the sleeve, to be moved rotatably, and cause the throttle valve to be opened in the manner already described. It will thus be evident that the throttle valve may be fully opened when either the handle 14, or pedal 20 are operated independently of the other.

With such an arrangement, however, the pedal might be accidentally depressed when the automobile was stationary and the operator unprepared to start the car. To obviate this danger, I so arrange the hand operated mechanism that the sleeve 19^a may be moved back of the neutral position, in which it will permit the spring 32 to close the throttle valve, so that when the handle 14 is moved in the direction to permit the throttle to close, this movement may be continued past the closed position causing the shoulder 19^c to be moved into engagement with the beveled face of the tooth 34 and depressing the same beneath the surface of the shaft, as shown in Fig. 6, in which position these parts may be permitted to remain, so

that in case the foot-operated rod 20 is depressed, and the sleeve 22^a is moved in a direction to rotate the shaft, it will simply pass over the tooth without engaging the same. The foot operated means will thus be rendered ineffective, so long as the handle 14 is in the retarded position of Fig. 6, but, as soon as the sleeve 19^a is returned to the neutral or intermediate position, the tooth will be forced out into position to be engaged by the shoulder 22^b.

It is to be further noted that the sleeve 19^a may be moved to a sufficiently retarded position to bring the shoulder 19^c into engagement with the pin 33, so that, in case the spring 32 should break or fail to act to close the throttle, the shaft 26 may be positively moved by the handle 14 in a direction to force the throttle into its closed position.

It is also to be noted in this connection that, if the pedal is held in depressed position, accidentally either by foot, or some obstruction, it may be disengaged from the tooth 34 by forcing the hand lever back to the retarded position, so as to press the tooth out of engagement with the sleeve 22^a, and permit the valve to close, or be positively forced to the close position by the action of the sleeve 19^a on the pin 33. 95

I claim:

1. In combination with a throttle valve actuating means, independent hand-operated, and foot operated controlling means therefor, and means for rendering said foot operated controlling means inoperative.

2. In combination with a throttle valve actuating means, independent hand-operated, and foot operated controlling means therefor, means operated by said hand operated controlling means for rendering said foot-operated controlling means inoperative.

3. In combination with a throttle valve, actuating means for moving said valve from its closed position, a foot operated controlling means, engaging means intermediate said actuating means and said controlling means normally arranged to be engaged by said controlling means to operate said actuating means, to move said valve to an open position, a hand-operated controlling means movable from an intermediate position, in one direction to operate said actuating means to open the throttle valve and in the opposite direction to move said engaging means out of position to be engaged by said foot operated means.

4. In combination with a throttle valve, actuating means for moving said valve from its closed position, a foot operated controlling means, an abutment interposed between said actuating means and said controlling means in position to be engaged by the latter to move the same to operate the former to open said throttle valve, a hand-operated 130

controlling means movably from an intermediate position, in one direction to operate said actuating means to open the throttle valve, and in the opposite direction to move said abutment out of position to be engaged by said foot operated controlling means.

5. In combination with a throttle valve a single actuating means for moving said valve to open position, a foot-operated controlling means and a hand-operated controlling means, separate engaging devices interposed between said foot-operated and said hand-operated means, respectively, and said actuating means, each in position to be engaged thereby to move said actuating means to open said throttle valve, said hand-operated means being movable, from an intermediate position, in one direction to operate said actuating means thru its corresponding engaging device, and in the opposite direction to move the other engaging device out of position to be engaged by said foot-operated means.

25 6. In combination with a throttle valve, a shaft and means actuated thereby when moved rotatably from its normal position to open said valve, a foot-operated controlling means and a hand-operated controlling means, separate abutments on said shaft arranged to be engaged by said foot and hand-operated means, respectively, when moved in one direction, from a neutral position, to operate said shaft, the abutment arranged to be engaged by said foot-operated means being movable out of engaging position by said hand-operated means when the latter is moved in the opposite direction.

7. In combination with a throttle valve, a shaft and means actuated thereby when moved rotatably from an initial position to open said valve, a pair of sleeves mounted for rotational movement on said shaft, two abutments mounted on said shaft and arranged to be engaged one by one of said sleeves and one by the other, when rotatably moved thereon in one direction from an initial position to operate said shaft, and means on one of said sleeves arranged to be engaged with the abutment of the other sleeve, when moved in the opposite direction from said position to move the same out of position to be engaged by its corresponding sleeve.

55 8. In combination with a throttle valve, a shaft and means actuated thereby when moved rotatably from an initial position to open said valve, a pair of sleeves mounted for rotational movement on said shaft, a fixed abutment and a depressed abutment mounted in said shaft, one arranged to be

engaged by one of said sleeves and one by the other, when moved in one direction from an initial position, to operate said shaft, and means on the sleeve for engaging said fixed abutment arranged to depress the other abutment into a position in which it will be disengaged from the other sleeve in all positions of the latter.

9. In combination with a throttle valve, a shaft and means actuated thereby for opening said valve when the shaft is moved rotatably from its initial position, a tooth mounted in said shaft having an abutting face at one side and a beveled face at the opposite side and adapted to be depressed from its abutting position, a pedal operated sleeve on said shaft arranged to be engaged with said abutting face to operate said shaft, a projection fixed in said shaft, a hand operated sleeve having oppositely disposed faces adapted to be engaged with said projection when moved in opposite directions from an intermediate position, and means on said hand-operated sleeve arranged to engage the beveled face of said tooth and depress the same from its abutting position when the sleeve is moved from its intermediate position in the opposite direction from that in which it is moved to open said valve.

30 10. In combination with a throttle valve, foot operated means and hand operated means each arranged to operate said throttle valve independently of the other, and means operated by said hand operated means when it is moved in a direction to close said valve to render said foot operated means inoperative.

11. In combination with a throttle valve, foot operated means and hand operated means each arranged to operate said throttle valve independently of the other, and means operated by said hand operated means when it is moved in a direction to close said valve, to disengage said foot-operated means from the valve when said foot operated means is in position to hold the valve open.

45 12. In combination with a throttle valve actuating means, foot operated controlling means, and hand operated controlling means for said actuating means, each arranged to operate the same independently of the other, said hand-operated means being movable from an intermediate position, in one direction to operate said actuating means, to open the throttle valve, and in the opposite direction to disengage said foot-operated means from said actuating means.

50 In testimony whereof, I have signed my name to this specification.

ERNEST PULSIFER.
